CLAIM

The ornamental design for a car headlight as shown and described.

DESCRIPTION

FIG. 1 is a perspective view of a car headlight showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the car headlight, shown with an unclaimed mirror image.

The broken line showing an additional headlight, in FIG. 9, illustrates environmental structure of the car headlight and form no part of the claimed design. All other broken lines illustrate portions of the headlight and form no part of the claimed design.
